TEXTILE

Ralph R. Cone, Augusta, Ga., assignor to Riverside Mills, Augusta, Ga., a corporation of Georgia

Application April 17, 1946, Serial No. 662,837

11 Claims. (Cl. 154—53.6)

1

This invention relates to textile products, apparatus and methods.

In U. S. Patent No. 2,344,537, dated March 21, 1944, in the name of the present inventor, there is described an article of manufacture comprising a textile filament wound and stitched to form a web suitable for varied uses in the textile art. In application Serial No. 575,232, filed on January 30, 1945, now Patent No. 2,482,655, and Serial No. 640,350, filed on January 10, 1946, now Patent No. 2,551,098, there appears a disclosure of the winding of a filament or filaments temporarily upon a mandrel and then manipulating the wound filament or filaments to define a product suitable for uses of the types contemplated by the patent above identified.

In accordance with the present invention it is proposed to provide apparatus, methods and products distinguishing from those of the aforesaid patent and applications, the product however being intended for analogous uses such as the manufacture of rugs of the type wherein the pile is adhesively secured to a suitable backing. Among other applications of the product of this invention are tapes, braid, tapestries, portiers, bed covers, trimmings, draperies, purses and other ornamental and utilitarian fabrics.

The product of the present invention comprises a helically arranged filament having one or more additional filaments extending through the helix and adhesively joined thereto. Where a tape-like body is contemplated, the wound filament defining the helix may be arranged as a substantially flat tube maintained in its substantially flat condition by the internal adhesively attached filaments. The internal filament or filaments may be located by means of suitable adhesive at the edges of the substantially flat tube, and where desired to thicken such a tube, one or more filaments may be adhesively applied externally of the tube along its upper and/or lower edges. In some cases, the helically arranged filament may comprise a relatively soft textile material such as worsted while the internal filament may be a relatively hard textile material such as jute. Any one or more of the filaments employed may be applied singly or plurally in twisted, knitted, braided or other suitable condition, and for purposes of this application, all are referred to as filaments.

A preferred method of practicing this invention contemplates advancing one or more filaments axially, winding another filament about it or them, with its adjacent convolutions in contact where desired, and adhesively joining ad-

2

jacent surfaces of the filaments. Where the products are to be split ultimately, as in the manufacture of rugs, a plurality of filaments such as two, are preferably used as a core about which the wound filament is arranged, the internal filaments being preferably in substantially parallel spaced relationship. In those cases requiring the application of external filaments for spacing or ornamental purposes, such filaments are applied to the wound body by means of an adhesive, at the edges of the substantially flat filaments have been shaped and assembled, pressure is preferably applied to achieve the desired adhesive bond. A highly satisfactory application of natural or synthetic rubber latex has been achieved by feeding the internal and any external filaments in such a way as to receive a coating of the adhesive prior to contact with the wound filament. The subsequent pressing by suitably grooved rolls, for example, serves also to feed the various filaments at the required rates.

Apparatus suitable for carrying out the present invention may comprise a mandrel provided with one or more guides for the internal filament or filaments, means for winding a filament about the mandrel and the internal filament or filaments and means for introducing an adhesive between the one or more internal filaments and the wound filament. Where external filaments are applied, means for applying the desired number will be provided together with means for introducing an adhesive between such external filament or filaments and the wound filament. Means is also contemplated for pressing the various filaments into contact so that they will be effectively joined by the previously applied adhesive.

A more complete understanding of the invention will follow from a detailed description of the accompanying drawings wherein:

Fig. 1 is an elevation partially in section depicting a form of apparatus suitable for carrying out methods and manufacturing products contemplated by the present invention;

Fig. 2 is a section taken along line 2—2 of Fig. 1;

Fig. 3 is a section taken along line 3—3 of Fig. 1;

Fig. 4 is a plan of one form of product;

Fig. 5 is an elevation of the product shown in Fig. 4;

Fig. 6 is a plan of another form of product;

Fig. 7 is an elevation of the product shown in Fig. 6;

Fig. 8 is a plan of another form of product; and

Fig. 9 is an elevation of the product shown in Fig. 8.

With reference to Figs. 1 to 3, a cage 20 is made up of end flanges 22 and 24 interconnected by rods or bars 26 provided in a number sufficient to produce adequate strength and at the same time afford access to the interior of the cage. The left end of the cage as viewed in Fig. 1 is provided with a hub 28, shown as drilled and threaded to receive a set screw 30 for securing the cage to a hollow rotary shaft 32. This shaft 32 is journaled in suitable bearings 34 carried by a pedestal 36. Intermediate its bearings 34, the shaft 32 carries a worm 38 in mesh with a wheel 40 fixed to a shaft 42. Also fixed to the shaft 42 is a sprocket 44 whose teeth cooperate with the links of a chain 46 extending behind the cage 20 to drive a sprocket 48 located at the right end of the cage.

The hub 28 and shaft 32 have been shown as drilled transversely at a slight inclination to provide a passage 50 and the flange 22 is drilled at its intersection with the upper rod 26 to define a passage 51, for a purpose to be described. The left end of the shaft 32 projecting beyond the pedestal has fitted thereto a pulley 52 for receiving a belt 54 driven by a pulley 56 mounted on the shaft of an electric motor 58.

The right end of the cage 20 terminates in a tubular shaft 60 which is supported in an outer bearing 62 fitted in a pedestal 64. The inner bore of the tubular shaft 60 receives a bearing 66 in which is journaled a tubular extension 68 for supporting the right end of a cradle 70. The left end of the cradle is supported through a suitable bearing 72 upon the inner end of the shaft 32 which projects a suitable distance within the case.

By virtue of the arrangement of bearings supporting the cradle 70, it will not partake of the rotation of the cage 20 and accordingly, will support a mandrel 74 in a substantially fixed position by means of a spider 76 provided near the end of the tubular extension 68. As shown in Fig. 2, the mandrel 74 is substantially flat having grooved edges to serve as guides for one or more filaments 78 delivered from reels 80 whose shafts 82 are received in bushings 84 provided in the upper edges of the cradle. The cradle 70 supports a fountain 86 in which a roller 88 is suitably supported for rotation in a body of adhesive 90 so that when the filaments 78 advance over the fountain roller 88, they will receive an application of adhesive for joining them to the filament 92 which is wound around them.

The filament 92 is supplied from a source 94 located at the left end of the apparatus depicted in Fig. 1. The filament 92 is threaded through the shaft 32 from which it is deflected through the passage 50 by means of a suitable tool, extending radially of the flange 22, through one of the rods or bars 26 which is made hollow for this purpose, to the flange 24 where it is deflected inwardly radially by means of a suitable tool inserted through an opening 96 adjacent the point at which the hollow rod or bar 26 adjoins the flange 24. The hollow extension 60 is likewise drilled longitudinally in order that the filament can be threaded through it by means of a suitable tool introduced through an opening 98 aligned with the drill opening through the hollow extension 60.

The sprocket 48 is suitably journaled in a pedestal 100 by means of a shaft 102 which carries in spaced relationship with respect to the

sprocket a grooved roll 104 whose periphery is received between the flanges 106 of a grooved roll 108 carried by a shaft 110 in the pedestal 100 by means of suitable bearings.

Peripheral grooves 112 provided in the upper roll 104 serve as guides for filaments 114 supplied from a source, not shown, between the roll 104 and an adhesive application roller 116 supplied with adhesive 118 from a fountain 120 by means of a fountain roller 122. Similarly, where outer filaments are to be applied to the lower surface of the wound body, they are fed into the grooves 124 of the lower roll 108. Such filaments 126 are drawn from a source not shown, and fed over an adhesive applying roller 128 fed by means of a fountain roll 130 with adhesive 132 provided in a fountain 134. Pressure adjustment 135 is provided for the rolls.

From the foregoing description of the apparatus, it will follow that when the various filaments are threaded in proper relationship with respect to the apparatus, when the motor 58 is energized it will drive the pulley 52 and rotate the cage 20 to wind the filament 92 from the source 94 about the mandrel 74 and the filaments 78 which are advanced longitudinally along the grooves or guides provided by the mandrel. Since the filaments 78 have adhesive material such as natural or synthetic rubber latex applied thereto, as the filament 92 is wound about them, the desired adherence will be effected by the pressure of the rolls 104 and 108 which may be adjustable in any suitable manner to accommodate varying thicknesses of material. Where outer filaments 114 are provided on the upper surface of the wound body and/or filaments 126 on the lower surface of the wound body, these are likewise supplied with a similar adhesive material from their respective fountains and are similarly pressed between the rolls 104 and 108 to the wound body whereby the desired unitary relationship is achieved.

Three examples of products produced in accordance with the apparatus and method hereinbefore described are depicted in Figs. 4 to 9 inclusive of the drawings. In Figs. 4 and 5 the tape-like body comprises a substantially flat tube formed from the filament 92 wound about a pair of filaments 78 extending through the helix adjacent the edges thereof.

In Figs. 6 and 7 a somewhat similar product is depicted, having in addition a pair of external filaments 114 joined to the upper surface for ornamental or spacing purposes.

In Figs. 8 and 9, a pair of external filaments 126 have been added to the lower surface of the tubular body, likewise for ornamentation and/or spacing functions.

In these Figs. 4 to 9 inclusive, the adhesive for uniting the various filaments has been depicted generally by reference character 136.

As previously stated, the filament 92 may in some instances be relatively soft textile material such as worsted while the internal filament or filaments 78 may be relatively hard textile materials such as jute. Such a combination of materials tends to lend stiffness to the finished product during further operations to which it may be submitted as in the manufacture of rugs, yet the ultimate pile of such a rug will be soft and relatively resilient. It should be understood however that the materials constituting the filaments may vary widely depending upon the application to which the product is to be put.

The apparatus, method and products described hereinabove are typical examples of the manner in which the present invention can be applied and are by no means exhaustive. Accordingly, the scope of the invention should not be limited to these examples beyond the scope of the appended claims.

I claim:

1. An article of manufacture comprising a textile filament helically arranged with successive convolutions substantially contacting one another in the form of a substantially flat tube and a filament extending through said tube and adhesively joined thereto to maintain said tube in substantially flat condition, said tube having an internal perimeter substantially greater than the perimeter of the filament extending therethrough.

2. An article of manufacture comprising a textile filament helically arranged with successive convolutions substantially contacting one another in the form of a substantially flat tube and a textile filament extending through said tube and adhesively joined thereto, said tube having an internal perimeter substantially greater than the perimeter of the filament extending therethrough.

3. An article of manufacture comprising a textile filament helically arranged with successive convolutions substantially contacting one another in the form of a substantially flat tube and spaced filaments extending through said tube and adhesively joined thereto along its edges.

4. An article of manufacture comprising a textile filament arranged in the form of a substantially flat tube and filaments secured thereto extending internally and externally along an edge of said tube.

5. An article of manufacture comprising a textile filament arranged in the form of a substantially flat tube and adhesively applied filaments extending internally and externally along an edge of said tube.

6. An article of manufacture comprising a textile filament arranged in the form of a substantially flat tube and filaments secured thereto extending internally and externally along the edges of said tube.

7. An article of manufacture comprising a textile filament arranged in the form of a sub-

stantially flat tube and adhesively secured filaments extending internally and externally along the edges of said tube.

5 8. An article of manufacture comprising a textile filament arranged in the form of a substantially flat tube and adhesively secured textile filaments extending internally and externally along the edges of said tube.

10 9. An article of manufacture comprising a textile filament helically wound with successive convolutions substantially contacting one another in the form of a substantially flat tube and a filament extending longitudinally within said tube along an edge thereof and adhesively secured to the convolutions of said tube, said tube having an internal perimeter substantially greater than the perimeter of the filament extending therethrough.

15 10. An article of manufacture comprising a relatively soft textile filament helically arranged with successive convolutions substantially contacting one another in the form of a substantially flat tube and a relatively hard textile filament extending through said tube and adhesively joined thereto, said tube having an internal perimeter substantially greater than the perimeter of the filament extending therethrough.

20 11. An article of manufacture comprising a textile filament helically arranged with successive convolutions substantially contacting one another in the form of a substantially flat tube and adhesively secured filamentary material extending through said tube in spaced relationship along its opposite edges.

Certificate of Correction

Patent No. 2,570,526

October 9, 1951

RALPH R. CONE

It is hereby certified that error appears in the printed specification of the above numbered patent requiring correction as follows:

Column 2, lines 11 and 12, for "adhesive, at the edges of the substantially flat ments" read *adhesive. In any case, after the component filaments*; and that the said Letters Patent should be read as corrected above, so that the same may conform to the record of the case in the Patent Office.

Signed and sealed this 22nd day of January, A. D. 1952.
